Term of patent 14 years

(Cl. D28—1)

FIG. 1

FIG. 4

FIG. 2

FIG. 5

Figure 1 is a front elevational view of a panel unit for a picket fence showing our new design.

Figure 2 is a rear elevational view thereof.

Figure 3 is an enlarged fragmentary vertical cross-sectional view taken on the lines 3—3 of Figure 2.

Figure 4 is an enlarged fragmentary horizontal cross-sectional view taken on the lines 4—4 of Figure 2.

Figure 5 is a top plan view thereof.

The characteristic feature of our design for a panel unit for a picket fence resides in the pickets appearing superimposed on the horizontal stringers when viewed from either side, as shown in Figures 1 and 2.

We claim:

The ornamental design for a panel unit for a picket fence, as shown and described.
